DESIGN FOR A BROOCH PIN OR SIMILAR ARTICLE

Marcel Boucher, Eltingville, N. Y., assignor to Mazer Brothers, New York, N. Y.

Application November 3, 1936, Serial No. 65,668

Term of patent 3½ years

To all whom it may concern:

Be it known that I, Marcel Boucher, a citizen of the United States of America, residing in Eltingville, Staten Island, county of Richmond, and State of New York, have invented a new, original, and ornamental Design for a Brooch Pin or Similar Article, of which the following is a specification, reference being had to the accompanying drawing, forming part thereof.

Fig. 1 in the drawing is a plan view of a brooch pin or similar article showing my new design.

Fig. 2 is an edge view of the brooch pin or similar article.

I claim:

The ornamental design for a brooch pin or similar article substantially as shown.

MARCEL BOUCHER.
